CLOSURE FOR MULTICOMPARTMENTED BOTTLE WITH MEANS FOR SELECTIVELY DISPENSING FROM ANY ONE OF SAID COMPARTMENTS

Richard Roubíček, Prague, Czechoslovakia, assignor to Československý Průmysl Lihovarský a drozdarský, Narodní Podnik, Prague, Czechoslovakia

Application March 1, 1950, Serial No. 146,935
In Czechoslovakia December 20, 1949

4 Claims. (Cl. 222—144.5)

1

This invention relates to closures for bottles having a plurality of chambers or compartments each adapted to contain a liquid, the liquids in the various chambers being ordinarily of different nature.

For closing the openings of the various chambers in the neck of the bottle stoppers have been hitherto used. For pouring liquid from one of these chambers or for filling such chambers the stopper of the particular chamber had to be removed. The use of such stoppers leads to difficulties which are particularly due to the small cross section of the individual openings in the bottle neck and to the smallness of the stoppers. To pour liquid from any of the chambers or compartments is also difficult because those parts of the partitions between the various chambers which are situated in the neck of the bottle extend lengthwise of that neck and part of the liquid is easily spilled when pouring such liquid, particularly into a small glass or the like.

It is an object of this invention to provide a closure for bottles having a plurality of chambers or compartments extending into the neck of the bottle, which closure will avoid the above mentioned difficulties.

More particularly, it is an object of this invention to provide a closure for bottles of the kind referred to wherein a disc having a single opening is arranged so that upon rotation of this disc its opening can be brought into communication with any desired one of the bottle chambers or compartments.

A further object of the invention is to provide a closure of the kind referred to comprising a cap having a plurality of passages each adapted to communicate with one of the chambers of the bottle and a disc having a single opening, which disc will keep closed either all the passages in the cap or, upon rotation of the disc through some angle, all said passages except for a selected single one.

A further object of the invention is to provide a closure for bottles having a plurality of chambers or compartments extending into the neck of the bottle wherein the above mentioned passages in the cap, and preferably also the single opening in the disc, are inclined outwardly in the direction away from the end of the neck of the bottle.

Other objects and advantages of the invention will appear as the description proceeds, reference being had to the accompanying drawing which, by way of example, shows one embodiment of the invention as applied to a bottle hav-

2

ing four chambers or compartments. In the drawing:

Fig. 1 is a perspective view of the closure and of a part of the bottle neck;

Fig. 2 is a vertical section along the line A—A in Fig. 1; and

Fig. 3 is a plan view.

The closure shown in the drawing comprises a cap 1 which may be secured to the neck 2 of a bottle by means of putty or the like. In the top 1' of the cap 1 four passages 3 are provided, each of these passages communicating with one of four channels 4 in the bottle neck 2 which four channels form the upper end of the four chambers or compartments in the body of the bottle (not shown). To secure a tight closure there is interposed between the top 1' of the cap 1 and the upper end of the bottle neck 2 a plate or washer 5 made of cork, rubber or the like and having holes corresponding to the passages 3 in the cap. The passages 3 are inclined outwardly in the direction from the end of the bottle neck 2 towards the upper surface of the cap.

Rotatably mounted in the center of the top 1' of the cap 1 by means of a pin 6 is a disc 7. A spring 8 pulls the disc 7 tightly against the top 1'. The disc 7 has an elongated opening 9 which is inclined outwardly in the direction from its bottom end towards its top end. Rigidly connected to the disc 7, e. g., made in one piece with the disc 7, is an arm 10 which extends downwardly along the side 1'' of the cap 1. The arm 10 is provided at its inner side with a snap 11 urged towards the side of the cap by a spring 12. In the path of the snap 11, when the latter is rotated together with the disc 7 and the arm 10, there are provided in the outer surface of the side 1'' of the cap 1 depressions 13. There are twice as many depressions 13 as there are passages 3, every second depression corresponding to a position of the disc 7 in which the opening 9 thereof is in communication with one of the passages 3, whereas the intermediate depressions correspond to those positions of the disc 7 in which all the passages 3 are closed by the disc 7. In the example shown, where there are four passages 3 corresponding to the four channels 4 in the bottle neck 2, the number of the depressions 13 is eight. When the snap 11 has snapped into any of the depressions 13 the position of the pouring opening 9 in the disc 7 relative to the various passages 3 in the cap 1 is securely fixed and it will take some effort to move the disc out of such position.

To indicate to the user which of the depres-

sions 13 corresponds to a particular passage 3 (and thereby to any particular chamber of the bottle), the depressions may be marked by identification markers such as indicated in the drawing at 14. When the arm 10 is over one of the markers 14 with the snap 11 snapped in, this indicates that the closure is in proper position for pouring liquid from the bottle chamber which the particular marker 14 indicates. When the snap 11 is in engagement with one of the depressions 13 between two markers 14, this indicates that all the passages 3 are closed.

The inclination of the passages 3 in the cap 1 and of the opening 9 in the rotatable disc 7 facilitates a safe pouring of the liquids also into small containers.

While I have shown in the drawing one particular embodiment of the invention, I desire it to be understood that this embodiment has been given by way of example only and that various changes and modifications of the details of the construction shown may be made without departing from the spirit of the invention or the scope of the appended claims.

What I claim is:

1. A closure for bottles having a plurality of chambers extending into the neck of the bottle, comprising a cap adapted to be secured to said neck of the bottle, a plurality of passages in the top of said cap each arranged for communication with one of said chambers in said bottle neck when said cap is in position upon said bottle neck, a disc rotatably mounted on said cap, a single opening in said disc so arranged as to be adapted to be brought into registering position with any one of said passages in said cap upon rotation of said disc about its axis, an arm rigidly connected to said disc extending downwardly along the side of said cap, a spring-loaded member carried by said arm, and a number of depressions in said side of said cap situated in the path of said arm when the disc carrying said arm is rotated, so that said member will snap into a desired one of said depressions when in registering position therewith.

2. A closure for bottles having a plurality of chambers extending into the neck of the bottle, comprising a cap adapted to be secured to said neck of the bottle, a plurality of passages in the top of said cap each arranged for communication with one of said chambers in said bottle neck when said cap is in position upon said bottle neck, a disc rotatably mounted on said cap, said passages being inclined outwardly in the direction from the end of the bottle neck towards said disc, a single opening in said disc so arranged as to be adapted to be brought into registering position with any one of said passages in said cap upon rotation of said disc about its axis, an arm rigidly connected to said disc extending downwardly along the side of said cap, a spring-loaded member carried by said arm and a number of depressions in said side of said cap situated in the path of said arm when the disc carrying said

arm is rotated, so that said member will snap into a desired one of said depressions when in registering position therewith.

3. A closure for bottles having a plurality of chambers extending into the neck of the bottle, comprising a cap adapted to be secured to said neck of the bottle, a plurality of passages in the top of said cap each arranged for communication with one of said chambers in said bottle neck when said cap is in position upon said bottle neck, a disc rotatably mounted on said cap, a single opening in said disc so arranged as to be adapted to be brought into registering position with any one of said passages in said cap upon rotation of said disc about its axis, said single opening being inclined outwardly in the direction from its bottom end towards its top end, an arm rigidly connected to said disc extending downwardly along the side of said cap, a spring-loaded member carried by said arm and a number of depressions in said side of said cap situated in the path of said arm when the disc carrying said arm is rotated, so that said member will snap into a desired one of said depressions when in registering position therewith.

4. A closure for bottles having a plurality of chambers extending into the neck of the bottle, comprising a cap adapted to be secured to said neck of the bottle, a plurality of passages in the top of said cap each arranged for communication with one of said chambers in said bottle neck when said cap is in position upon said bottle neck, a disc rotatably mounted on said cap, said passages being inclined outwardly in the direction from the end of the bottle neck towards said disc, a single opening in said disc so arranged as to be adapted to be brought into registering position with any one of said passages in said cap upon rotation of said disc about its axis, said single opening being inclined outwardly in the direction from its bottom end towards its top end, an arm rigidly connected to said disc extending downwardly along the side of said cap, a spring-loaded member carried by said arm and a number of depressions in said side of said cap situated in the path of said arm when the disc carrying said arm is rotated, so that said member will snap into a desired one of said depressions when in exact registering position therewith.
